MOLDING APPARATUS

Friedrich Rolff, Berlin-Frohnau, Germany, assignor to The Osborn Manufacturing Company, Cleveland, Ohio, a corporation of Ohio

Application December 15, 1930, Serial No. 502,524.
Renewed December 20, 1932. In Germany December 16, 1929

6 Claims. (Cl. 22—36)

The present invention concerns a new method and new means for the filling of mold boxes or core boxes with mold substances such as sand and the like, by pneumatic action.

5 Mold machines in which the mold filling substance, usually sand, is forced from a sand chamber into the core box or mold box by compressed air have suffered frequently from the defect of uneven blowing. Too much air gets into the
10 mold box or core box with too little mold sand. It is known, in order to remedy this defect, to press the mold sand in the sand chamber before blowing, but this has given rise to the difficulty that the air, when first applied, could not force
15 its way through the sand. After the air pressure had been applied long enough to move the sand, the result was objectionable in that the sand was not all blown out, but craters formed in the sand in the chamber in spite of the previous compression, and these craters enlarged, releasing the pressure above the sand, so that the sand chamber was not entirely emptied and the mold box or core box was not properly and completely
20 filled.
25 Mechanical means have also been used for driving the mold filling material, but in the present invention mechanical means are used solely to keep the material properly conditioned for pneumatic propulsion, the flow of the material
30 being caused solely by the action of the compressed air.

In the accompanying drawing the invention is shown by way of example:

Fig. 1 is a front elevation showing the arrangement of components of the mold machine.

Fig. 2 is the plan of Fig. 1.

Fig. 3 is a section through the mold substance container along *a—b* of Fig. 1.

Fig. 4 is a section through the cylinder head of
40 the rising and falling cover, according to *c* and *d* of Fig. 1, and

Fig. 5 shows the operating valve in cross section through *e* and *f* of Fig. 2.

1 denotes the base of the mold machine. On
45 this base 1, columns 2 and 3, are firmly supported in a vertical position. The upper ends of the two columns are connected with each other by a bridge 5, which in the middle is shaped into the air cylinder 4. In the centre of the column, the mold substance container 6 is mounted so as to be vertically movable by the aid of the guide arms
50 7 and 8.

The mold substance container 6 is held at a given height by two compression springs 9 and 10
55 slipped on to the column, and engaging beneath

the guide arms 7 and 8. The mold substance container 6 is closed at bottom by a bottom 11. In this bottom outlet openings 12 for the mold substance are provided. The upper opening of the mold substance container is during the work of molding closed by a cover 13 which can rise and fall. The cover 13 is guided in the cylinder head 4 by the aid of a piston 14 and the hollow piston rod 15. The cover 13 has a passage 16 for compressed air. Compressed air from a control valve 17 is led to this passage 16 by a pipe 18, the upper portion of which is flexible. In the interior of the mold agent container 6, a means for stirring the mold sand is provided. This means for stirring the sand consists mainly of 15 agitator arms 19 which are fixed on a shaft 20. The shaft 20 passes through the hollow piston rod 15 of the cover and thus through the cylinder 4, and is coupled at the upper end with a worm wheel 22. The worm wheel 22 is connected 20 through a worm 23 operatively with the electric motor 24. In order that the stirring means 19 provided in the interior of the mold material container 6 should participate in the vertical movement of the container, the upper end of the 25 shaft 20 is journaled in a yoke 25. This yoke 25 is carried by the upper ends of two vertical rods 26 and 27 fixedly mounted on the container. These rods 26 and 27 are guided in the bridge 5 by guide bearings 28 and 29. The cover 30 of the 30 pneumatic cylinder 4 has an inlet 31 for compressed air. Air is supplied to this inlet by a pipe 32 from the control valve 17.

A truck 34 is movable on tracks 33 on the base 1. This truck includes a table 35, adjustable in height, which serves to support a core box 36. As here shown this core box is of two-piece construction, the pieces of which can be clamped together by suitable means such as 37, adjustable in height on a post 38 (Fig. 2) rising from the base 1. In the present embodiment such means consist of screw-adjustable jaws 39 carried by piston rods 41, the pistons 42 of which move in cylinders 40. A compressed air duct 43 connected with the controlling valve 17, carries compressed air into the cylinders of the clamp and drives the gripping jaws against the faces of the mold box. The body 17' of the valve 17 is rotatable in its casing by a handwheel 51. The body 17' is hollow and is closed except for four ports. 45 Air is supplied to the interior of the valve by a circumferential groove 50' and a port 50" connected therewith, the groove being positioned opposite the outlet of a compressed air supply pipe 50. By turning the valve body 17' air is 50 supplied to the interior of the valve by a circumferential groove 50' and a port 50" connected therewith, the groove being positioned opposite the outlet of a compressed air supply pipe 50. By turning the valve body 17' air is 55

successively admitted through ports 44, 45 and 46 to pipes 43, 32 and 18, respectively; first setting the clamp 37 to hold the core or mold closed and in place; next moving the piston 14 down to close the cover 13 on the mold substance container; and finally admitting compressed air into the top of the container 6 to blow the core. When the valve is in the position of Fig. 5, sand is being blown from the container 6 into a core or mold. The valve position of Fig. 5 does not correspond to the positions of the various parts in Figs. 1 and 4.

To stop blowing and open the machine, the valve body 17' is rotated in the opposite direction; thus first cutting off the air supply from the pipe 18, and at the same time venting that pipe (and through it the container 6) through the channel 49 on the outer surface of the valve body 17'; second, venting the pipe 32 through the channel 48 and so permitting the lid 13 to be lifted by hand or otherwise; third, venting the pipe 45 and so releasing the clamp 37. For filling the mold substance container 6 a mold substance carrier 52 is fitted on the column 2 of the molding machine so that it can be swung away from the machine by means of the bearing 53. In the mold substance container 6, there is inserted a part 54 expanding conically downwards, above which the mold substance is by the aid of the compressed air made dense and compact towards the outlet openings 12 of the bottom 11, before the mold substance is forced out of its container.

The above described molding machine which serves as a constructional example of the present invention, works in the following way:—

In the first place, the mold substance container 6, which is mounted so as to be movable up and down on columns 2 and 3 of the base 1, is preferably completely filled with sand. This is done by means of the mold substance carrier 52, mounted so as to be pivoted about the column 2 of the base 1. The valve 17 controlling the machine is now turned by means of the hand-wheel 51 fastened to it. Compressed air is fed through the pneumatic duct 50 to the control valve 17. The control valve 17 distributes this compressed air fed in and in the first place delivers it to the clamp 37 mounted on the base 1, in order to grip together at the sides the mold box 36, which is beneath the mold substance container 6. A further actuation of the controlling valve 17 supplies compressed air above the piston 14 whereby the cover 13 is pressed down onto the edge of the mold substance container, the latter being shut off at the top and at the same time moved vertically until the bottom of the mold substance container rests on the upper edge of the mold box and in this way also shuts off the upper face of the mold box. The controlling valve is then turned further so that compressed air is also conducted through the rising and falling cover 13, into the mold substance container 6. Simultaneously with this supply of compressed air into the mold substance container the agitator provided in the latter container is set in motion by the electric motor, so that now the compressed air, by the aid of the agitator, continuously forces the mold substance conducted along over the outlet openings of the container bottom, through such openings into the adjoining mold or core boxes. When the mold box is filled, the controlling valve is again actuated, whereby the screw clamp is discharged of air and the mold box released at the sides. The air is then released from the upper part of the cylinder 4 whereupon the

cover 13 goes upwards and the mold substance container is pressed upwards by the force of the two pressure springs 9 and 10. The mold box is therefore now also released in the vertical gripping direction and can be run out of the machine on the roller-mounted table. By proportioning the speed of rotation and the design of the agitator provided in the mold substance container it is possible as will be immediately understood, to determine the density of the mold substance in the container in such manner that the compressed air acting on the mold substance is not able to penetrate the latter but chiefly exercises a surface pressure.

It will be seen from the foregoing that the machine is capable of making either cores or molds, according to whether a core box or a mold flask is placed on the table 35. It is contemplated that cores will be the more usual product. Accordingly, in the specification and claims the terms "mold", "molding", etc., are to be interpreted so as to include and apply to cores and core making as well as to molds, "mold flask" and "core box" are used interchangeably, and so on, it being understood that a core is a specific instance of the general class of molds. In like manner, the term "sand" is used as designating either sand specifically or any other mold making or core making substance or material suitable for the purposes of this invention.

I claim:

1. In a molding machine, means to hold a core box, a sand container above the core box having a bottom provided with openings and also having a stirring element arranged to move on the bottom and over and across the openings and means to direct compressed air downwardly through the said container so that such compressed air acts on the upper surface of the sand in the container and causes the sand to be discharged therefrom into the core box through said openings together with compressed air while the sand is being kept in motion by the stirring element.

2. A molding machine as claimed in claim 1, including means to raise and lower the sand container and also including fluid pressure actuated means to permit the stirring element to be also raised and lowered.

3. A molding machine as claimed in claim 1, including means to raise and lower the sand container and also including fluid pressure actuated means to permit the stirring element to be also raised and lowered and comprising vertical guides on which the sand container is mounted, a cylinder mounted on said vertical guides, a piston in said cylinder, a cover for the sand container movable and carried by said piston, means to supply compressed air to the cylinder above the piston and means connected to the cover of the sand container to discharge compressed air into the sand container and in which the stirring element is revoluble in the sand container and has a vertical shaft extending up through the cover of the container and through the cylinder and piston.

4. A core or mold blowing machine comprising, in combination, a pressure-tight sand container, a top therefor, means for moving said top axially relatively thereto, an agitator in said container, and driving means for said agitator external to said container.

5. A core or mold blowing machine comprising, in combination, a sand container, bottom openings therein too small to permit flow of molding sand by its own weight, means below said con-

tainer for clamping a core box or mold flask against the bottom thereof, a rotor in said container, an axial shaft for said rotor, a top for said container movable along said shaft, a flexible air pressure connection to said top, a piston above said container for moving said top, and means for rotating said shaft.

6. In a molding machine, means to hold a core box, a sand container above the core box having a bottom provided with openings and also having 10 a stirring element arranged to move closely ad-

jacent the bottom and over and across the openings and means to direct compressed air downwardly through the said container so that such compressed air acts on the upper surface of the sand in the container and causes the sand to be discharged therefrom into the core box through said openings together with compressed air while the sand is being kept in motion by the stirring element.
